TUBE FORMING APPARATUS

Leonard J. Kowal, Prospect Heights, Ill., assignor to Imperial-Eastman Corporation, a corporation of Illinois
Filed Dec. 16, 1959, Ser. No. 859,983
6 Claims. (Cl. 153—80.5)

This invention relates to tube forming apparatus and in particular to swaging apparatus for forming the end of a tube.

One method of joining tubes of similar diameters is to enlarge one end of one tube permitting the end of the other tube to be inserted telescopically thereinto and secured therein as by soldering. The present invention is concerned with a forming apparatus for effecting the desired enlargement of the one tube end.

A principal object of the invention is, therefore, to provide a new and improved tube forming means.

Another object is to provide such a tube forming means including a graduated set of swaging adapters providing improved facilitated forming of each of a plurality of tubes having different diameters.

A further object is to provide such forming means wherein the set of adapters is arranged for improved functional association with the means supporting selectively the adapters in the tube forming apparatus.

Other features and advantages of the invention will be apparent from the following description taken in connection with the accompanying drawing wherein:

FIG. 1 is an elevation of a set of swaging adapters embodying the invention;

FIG. 2 is a fragmentary section of a tube forming apparatus embodying the invention, as arranged for forming the end of one size tube;

FIG. 3 is a view similar to that of FIG. 2 but illustrating the arrangement of the tube forming apparatus and tube end as at the completion of a forming operation; and

FIG. 4 is an enlarged fragmentary section of the tube forming apparatus illustrating the forming of a different sized tube.

In the exemplary embodiment of the invention as disclosed in the drawing, a tube forming apparatus generally designated 10 includes a base 11 having an upstanding portion 12 provided with a bore 13 through which is axially slidable a cylindrical support 14. Tube clamping apparatus generally designated 15 is further carried on base 11 for supporting a tube end T adjacent base portion 12 coaxially of support 14. Tube clamping means 15 may comprise a tube clamping means such as disclosed in co-pending George E. Frank application, Serial No. 855,639, filed November 27, 1959 and assigned to the same assignee as is this application. The tube clamping means 15 includes a plurality of paired blocks arranged for selective clamping of each of a plurality of different diameter tubes. Illustrated in FIGS. 2 and 3 is one such clamping block 16 for use with a $\frac{5}{16}$ " nominal diameter tube T; illustrated in FIG. 4 is another such clamping block 17 for use with a larger $\frac{5}{8}$ " tube T'. Also carried on base 11 is an operating means comprising a cam 18 movable by a manually operable handle 19 to engage the cam with an enlargement 20 at the outer end of support 14 and force the support longitudinally toward tube T. The support is biased outwardly into engagement with cam 18 by means of a helical compression spring 21 extending between base portion 12 and support enlargement 20.

Tube forming apparatus 10 further includes a graduated set 22 of swaging adapters herein identified as adapters 22a, 22b, 22c and 22d. The use of adapter 22c in forming the end of tube T is illustrated in FIGS. 2 and 3, and the use of adapter 22d in forming the end

2

of tube T' is illustrated in FIG. 4. The adapters are provided with similar shank portions 23 arranged to have a loose fit in a coaxial recess 24 opening into the inner radial end surface 25 of support 14. Shank 23 is loosely retained in recess 24 by a pin 26 passing freely through shank 23 and fixed in opposed radial holes 27 in support 14. A compression spring 28 is received in a reduced diameter extension 24a of recess 24 at the outer end thereof to urge shank 23 to a position wherein it projects partially from support surface 25, as shown in FIG. 2.

Each adapter is provided at the end opposite the shank 23 with a swaging nose portion; the nose portion of each adapter of set 22 differs from the others thereof, nose portion 29a of adapter 22a being adapted for use with a small diameter tube, nose portion 29b of adapter 22b being adapted for a larger diameter tube, nose portion 29c of adapter 22c being adapted for use with a still larger diameter tube, and nose portion 29d of adapter 22d being adapted for use with the largest diameter tube. Each nose portion includes a frusto-conical inner end portion 30 widening outwardly toward shank 23, a frusto-conical midportion 31 narrowing outwardly toward shank 23 from inner end portion 30, a cylindrical midportion 32 having a diameter less than the maximum diameter of inner end portion 30 and extending outwardly from frusto-conical portion 31, and a frusto-conical, outer end portion 33 widening outwardly toward shank 23 from cylindrical midportion 32. Each of the smaller sized adapters, namely adapters 22a, 22b and 22c is further provided with an annular collar portion 34a, 34b and 34c, respectively, intermediate outer end portion 33 and shank 23. Each collar portion includes a radial surface 35 facing the nose of the adapter. As best seen in FIG. 1, the axial length of the collars are inversely related to the nose diameters,

The use of tube forming apparatus 10 in forming tubing corresponding in diameter selectively to one of adapters 22a, 22b or 22c is illustrated in FIGS. 2 and 3 as each of the two smaller sized adapters functions similarly to adapter 22c shown therein. More specifically, tube T is clamped in the clamping device 15 with the tube forming apparatus 10 arranged as shown in FIG. 2. Handle 19 is then swung from the position of FIG. 2 to the position of FIG. 3 causing cam 18 to force support 14 to the left and urge nose 29c into the end of tube T. During the initial movement of the support 14, the clearance between support surface 25 and collar 34c is taken up permitting the nose portion 29c to center itself in the tube end. When collar 34c abuts surface 25, the adapter becomes longitudinally fixed on the support and further advance of the support causes the adapter nose end 30 to enter into and form the tube end.

As best seen in FIG. 3, at the completion of the forming operation, the tip 36 of tube T is flared outwardly by its engagement with the frusto-conical portion 33 of the nose. As the tip 36 passes beyond nose portion 30 to around portion 32, it constricts slightly due to the natural resiliency of the tube material. The frusto-conical portion 33 enlarges the tip portion 36 slightly to permit a facilitated withdrawal of the adapter nose from the tube end, and assure facilitated insertion of another tube end in the thusly enlarged end of tube T. The completion of the forming operation is positively indicated by the abutment of tip 36 with the surface 35 of collar 34c effectively assuring a proper, full forming of the tube end even by non-skilled persons.

Adapter 22d which corresponds to the largest diameter tube is not provided with a collar portion. However, the maximum diameter of the outer frusto-conical portion 33 thereof is smaller than the diameter of support 14 thus permitting the tip 36' of tube T' to abut support surface 25 at the completion of the forming operation to

provide the positive indication thereof. By thus arranging the set 22 of adapters so that the largest size adapter requires no collar, the over-all length of each of the adapters is effectively minimized providing facilitated manufacture and utilization. Further, by varying the longitudinal extent of the different collars inversely to the diametric size of the adapter, the over-all length of the different adapters of set 22 may be made comparable while yet the longitudinal extent of the enlargement of the tube end is proper for each of the different diameter tubes formed therewith.

While I have shown and described one embodiment of my invention, it is to be understood that it is capable of many modifications. Changes, therefore, in the construction and arrangement may be made without departing from the spirit and scope of the invention as defined in the appended claims.

I claim:

1. Tube forming apparatus comprising: means for holding a tube having any one of a plurality of different diameters; a support; means associated with the holding means and support for forcing the support coaxially toward the end of a tube in the holding means; and a graduated set of swaging adapters, each adapter having a similar shank portion for attaching selectively the adapters coaxially to the support, each adapter having a swaging nose portion, the nose portion of each adapter of the set differing from the others thereof for use with a corresponding diameter tube of said plurality, the adapter corresponding to the smallest diameter tube having a collar intermediate the nose portion and shank portion thereof to abut the end of the tube when the nose portion thereof is inserted sufficiently into the tube end to effect the forming thereof, the adapter corresponding to the largest diameter tube having a nose portion extending fully to the shank portion to permit the support to abut the end of the tube when the nose portion thereof is inserted sufficiently into the tube end to effect the forming thereof, and the adapters corresponding to tube diameters intermediate the smallest and largest diameters each having a collar the relative longitudinal extents of which differ inversely to the corresponding tube diameters.

2. The tube flaring apparatus of claim 1 including means securing the shank of any one of said adapters to said support which means biases the adapter to project partially outwardly from the support toward the tube end prior to engagement of the nose of the adapter with the tube end and which permits the adapter to be forced back relative to the support by the engagement of the nose of the adapter with the tube end until the portion of the adapter immediately outwardly of the shank abuts

the support to provide a longitudinally fixed carrying of the adapter on the support in completing the forming advance of the adapter into the tube end.

3. The tube forming apparatus of claim 1 wherein the end of the nose portion of each adapter closest the shank portion thereof flares outwardly toward the shank to enlarge the tube end thereat and facilitate withdrawal of the tube end from the adapter upon completion of the forming operation.

4. The tube forming apparatus of claim 1 wherein the portion of each adapter closest the shank portion thereof is transversely substantially larger than the shank portion.

5. The tube forming apparatus of claim 1 wherein the nose of each adapter includes a frusto-conical, inner end portion widening outwardly toward the shank, a mid-portion having a diameter less than that of the outer extremity of the inner end portion, and an outer end portion widening outwardly toward the shank to enlarge the tip of the tube end being flared for facilitating withdrawal thereof from the adapter upon completion of the forming operation.

6. The tube forming apparatus of claim 1 wherein the nose of each adapter corresponding to tube diameters smaller than the largest diameter includes a frusto-conical, inner end portion widening outwardly toward the shank, a mid-portion having a diameter less than that of the outer extremity of the inner end portion, and an outer end portion widening outwardly toward the shank to enlarge the tip of the tube end being flared for facilitating withdrawal thereof from the adapter upon completion of the forming operation, and the collar thereof is disposed intermediate the outer extremity of the nose outer end portion and the shank, the collar having a radial surface facing the nose for positively limiting the insertion of the nose into the tube end by engagement of said surface with the tip of the tube end.
